FILLING END CONTROLLER

Filed March 23, 1927 2 Sheets-Sheet 2

UNITED STATES PATENT OFFICE.

JOHN T. KIRK, OF NEW BEDFORD, MASSACHUSETTS, ASSIGNOR TO DRAPER CORPORATION, OF HOPEDEALE, MASSACHUSETTS, A CORPORATION OF MAINE.

FILLING-END CONTROLLER.

Application filed March 23, 1927. Serial No. 177,570.

This invention relates to filling replenishing looms and is more especially directed to the means for controlling the filling ends on replenishment of filling that they may not 5 be carried into the cloth.

It is now the common practice to provide filling replenishing looms with means for preventing the incoming or outgoing filling end from being taken into the shed with the 10 shuttle on a subsequent pick after replenishment. Should either of the pieces of filling end be carried into the shed, defective cloth will result.

The outgoing filling end is very frequent- 15 ly carried with the ejected bobbin and withdrawn from the shuttle box and shuttle eye, but dependence cannot always be placed upon this conditional operation especially with some characters or kinds of filling.

20 The incoming filling end which is usually secured to some fixed point, such as the outer end of the hopper or hopper stand, presents some difficulties also in preventing the part of the filling leading from the fixed point to 25 the cloth selvage from being taken into the shed on a subsequent pick following replenishment.

20 The present invention has for one of its objects to provide means for taking care 30 of and controlling the filling end whether it be the incoming or outgoing filling end, to prevent either from being taken into the shed.

35 More particularly the present invention provides a filling end controller which shall have an oscillatory movement upon a fixed point or pivot and so connected to the lay that upon movement of the latter the filling end controller will be given a sweeping 40 movement to engage and withdraw the filling end from the lay.

The various features of the invention and new combination of parts will best be made clear from the following description and 45 the accompanying drawings of one good form thereof.

In the drawings:

Fig. 1 is a perspective view of a portion of a loom at the replenishing side, provided 50 with the present invention;

Fig. 2 is an enlarged perspective view looking rearwardly and to the right at the replenishing side of the loom, and showing more particularly the filling end controller 55 for removing the incoming filling;

Fig. 3 is an enlarged sectional elevation looking towards the hopper or magazine and showing the present invention, the lay being in its backward position; and

Fig. 4 is a detail with parts broken away 60 showing the relation of parts when the lay is in its front position.

The loom frame 1 may be of usual construction and mounted at one side thereof is the hopper stand 2 in which a number of 65 filling carriers or bobbins 3 are carried. The end *a* of the filling leading from the filling carriers in the hopper is herein shown as carried over a disk 4 and an outer disk 5 and secured centrally of the hopper axis, as 70 at 6, by being twisted about a hub portion at the outer side of the disk 5. These details may be greatly varied, but they illustrate one means of supplying filling carriers 75 for replenishment of filling and also of securing the filling ends.

The magazine or hopper in the present instance of the invention is shown as of the rotary type and so, as these successive filling carriers are transferred, the filling end *a* 80 leading from the carrier next to be transferred will obviously be at the lower portion of the disk 5 in case such disk be employed. On replenishment of filling, when the filling carrier is transferred from the hopper to 85 the shuttle, the end leading therefrom and secured at the point 6, will cause the filling end *a* to take position as indicated in Fig. 1, as the shuttle is picked; that is, the filling *a* of the incoming filling carrier will take an 90 inclined position above the shuttle box, and unless the length of filling between the cloth selvage and the fixed point be removed, it is liable to drop into the path of the shuttle or the danger zone and be carried into the shed, 95 a condition that is particularly liable to occur when the temple thread cutter parts the filling end at the cloth selvage, or even should the filling end be broken.

Mounted upon the breast beam of the loom 100 is the temple stand 7 which may have the usual temple thread cutter, so that both the incoming filling end and the outgoing filling end may be severed at the cloth selvage.

Pivotaly mounted at 8 is the filling end 105 controller 9, the downwardly extending end portion 10 of which is adapted to engage the filling end *a* of the incoming filling when replenishment has been effected. The piv- 110

ably, though not necessarily, formed by an arm 11 which may be secured by a nut 12 to the stud shaft 13 of the rotary hopper.

Secured at the front of the loom and preferably on the breast beam is a thread catcher 14 which may be constituted as a wire finger bent upwardly at 15 and then reversely bent, as at 16, to form a catcher for the filling ends delivered to it by the filling end controller 9. In the present instance, the catcher 14 is secured by a bolt 17 to a fixed part of the loom and extends rearwardly a sufficient distance to permit the swinging controller 9 to carry the end of filling into engagement with the catcher when filling replenishment has been effected.

In order that the filling end controller 9 may be given a sweeping action transversely of the lay to engage the incoming filling end when filling replenishment is effected, the present invention contemplates that the filling end controller shall be so connected to the lay that its filling engaging end will sweep transversely over the path of movement of the incoming filling end on the first pick of the shuttle following replenishment, and to insure that the engaged filling end shall be swept forwardly into control of the filling end gatherer, the means for actuating the filling end controller is contrived to impart to the lower end thereof a sweeping movement forwardly to carry the end of the engaged filling into the thread gatherer.

In the present instance of the invention, the shuttle box 18 which is carried by the lay 19, as usual, has projecting upwardly therefrom the rigid arm 20 having a lateral extension 21 provided with an opening 22 through which opening 22 extends the filling end controller 9. The rigid arm 20 may be secured to the top of the shuttle box or to the lay in any suitable position by means of a screw or other securing means 23. It will be noted that the filling end controller 9, which is pivotally mounted at the fixed point 8, is engaged with the actuating arm or member 20 at a point between the pivot of the controller and its lower filling engaging end, the result being that the lower end portion of the controller will be given a movement in the same direction as the lay but at a greater speed, to the end that on forward movement the filling end engaged by the filling end controller will be swept forwardly and into the control of the thread catcher.

From the construction thus far described it will be apparent that the incoming filling end will be engaged by the filling end controller through its sweeping action and at a greater speed than the lay movement will be carried forwardly and held in its front position by the thread gatherer, so that at a subsequent period the temple thread cut-

ter may act upon the filling end to sever it at the cloth selvage.

The outgoing filling end is withdrawn from the lay in a corresponding manner to that of the incoming filling end; that is to say, the outgoing filling end is engaged by a yarn controller which is pivotally mounted at a fixed point and is given a swinging movement in a direction transversely of the lay to withdraw the filling end from the lay and shuttle box.

As indicated more clearly by Figs. 1 and 3, the outgoing filling end controller 24 is pivotally supported at 25 upon a bracket 26 which is secured to the loom frame as by the bolts 27, and the top edge portion of the end controller 24 is provided with a series of teeth 28. A light spring 29 normally holds the controller 24 in its normal position to receive over the top thereof the ejected filling carrier.

Extending downwardly from the controller 24 is the lug 30 having an eye through which extends an actuating rod 31, the outer portion of which is screw-threaded and provided with adjusting nuts 32. The actuating rod 31 is constituted as a rigid member and extends rearwardly and then upwardly, as at 33, and is fixedly secured to the lay 19 at 34, the effect being that on each backward movement of the lay, the controller 24 will be given a sweeping movement transversely of the lay in a direction to withdraw the filling end from the danger zone where it would be liable to be carried into the shed by the shuttle.

What is claimed is:

1. In a filling replenishing loom, the combination of the lay and shuttle box, a filling end controller comprising an oscillating member pivotally supported at a fixed point on the loom, a rigid member carried by the lay and movable therewith throughout the weaving operation, and continuous operative connections between said rigid member and the filling end controller for oscillating the filling end controller by lay movement following every pick of the shuttle to withdraw the filling end from the shuttle box should replenishment of filling occur.

2. In a filling replenishing loom, the combination of the lay and shuttle box, a filling end controller pivotally mounted at a fixed point above the lay and provided with a downwardly extending portion to engage the filling above the shuttle box, and means secured to the lay and positively connected to the filling end controller to cause the latter to sweep over the shuttle box on every lay movement to withdraw a filling end.

3. In a filling replenishing loom, the combination of replenishing mechanism, a filling end controller pivotally supported at a fixed point above the lay and having a downwardly extending filling engaging por-

tion, and positively sliding connections between the lay and filling end controller to impart to the latter a frontward sweeping movement relative to the lay during every beat-up of the lay to remove a filling end frontward of the lay.

4. In a filling replenishing loom, the combination of filling replenishing mechanism, a filling end controller pivotally mounted above the lay, a filling engaging arm, a rigid member secured to the lay and positively connected to the filling engaging arm above its filling engaging end to impart a sweeping movement thereto on every beat up movement of the lay to advance the engaged filling frontward relative to the lay.

5. In a filling replenishing loom, the combination of replenishing mechanism, a filling end controller pivotally supported at a fixed point above the lay and having a downwardly extending filling engaging portion, continuous connections between the lay and the filling end controller to impart to the latter a frontward sweeping movement relative to the lay during every beat-up movement of the lay to remove a filling end frontward of the lay, and means for retaining the filling end in front position as the filling end controller moves back.

6. In a filling replenishing loom, the combination of a filling end controller pivotally mounted for sweeping movements transversely across the lay and having a part for engaging the incoming filling, and means secured to the lay and also continuously connected to the filling end controller to impart such movements on every beat up of the lay that the engaged filling may be swept frontward of the lay at any time replenishment occurs.

7. In a filling replenishing loom, the combination of a filling end controller pivotally mounted for sweeping movements transversely across the lay and having a part for engaging the incoming filling, and means operated by the lay and positively connected to the controller for imparting said

sweeping movements on every beat up of the lay.

8. In a filling replenishing loom, the combination of a filling end controller pivotally mounted for sweeping movements transversely across the lay and having a part for engaging the incoming filling, and means carried by the lay and having a positive and sliding connection with the controller for imparting sweeping movements thereto on every beat up movement of the lay that an engaged filling end may be swept frontward of the lay.

9. In a filling replenishing loom, the combination of a filling end controller pivotally mounted for sweeping movements transversely across the lay and having a part for engaging the incoming filling, means connected to the lay and having a continuous sliding connection with the filling end controller to impart such movements thereto on every beat up of the lay that the engaged filling may be swept frontward of the lay, and separate means for retaining the filling in front position.

10. In a filling replenishing loom, the combination of a filling end controller pivotally mounted above the field of lay movements, an arm mounted on the lay and having an opening through which the controller extends for imparting movements of the lay on every beat up movement of the lay there- to at increased speed that the controller may move with and at higher rate of speed than the lay.

11. In a filling replenishing loom, the combination of the lay and shuttle box, a filling end controller comprising an arm pivotally mounted at a fixed point relative to the lay, and a controller actuator formed as an arm mounted on the lay and having a horizontal portion provided with an opening through which the filling end controller extends for positive actuation on every beat up movement of the lay.

In testimony whereof, I have signed my name to this specification.

JOHN T. KIRK.
